UNITED STATES PATENT OFFICE.

LINZY HICKS, OF OMAHA, NEBRASKA, ASSIGNOR OF ONE-HALF TO GEORGE VANSANT,
OF OMAHA, NEBRASKA.

WALL-LINING.

1,326,054.

Specification of Letters Patent. Patented Dec. 23, 1919.

Application filed April 16, 1918. Serial No. 228,893.

To all whom it may concern:

Be it known that I, LINZY HICKS, a citizen of the United States, residing at Omaha, in the county of Douglas and State of Nebraska, have invented certain new and useful Improvements in Wall-Linings; and I do hereby declare the following to be a full, clear, and exact description of the invention, such as will enable others skilled in the art to which it appertains to make and use the same.

The present invention relates to linings for the walls of refrigerators, cooling rooms, houses, and the like where heat insulation is desired.

The object is to provide an insulating lining of this character which is made up of blocks adapted to be assembled in interfitting relation for adapting the lining to angles, corners, and various configurations of a wall for effectually insulating the wall against passage of heat therethrough; to provide a lining which is composed of a multiplicity of cellular blocks, the spaces of which are adapted to be closed and sealed by the interfitting and securing of the blocks together; and to provide a wall lining block constructed of fibrous cellular material so arranged as to produce a relatively strong and durable block capable of withstanding considerable pressure.

A further object is to peculiarly form the fibrous cellular block so that when a pair of blocks is arranged in end abutting relation a plastic adhesive may be applied to the abutting ends of the blocks with the adhesive closing the pores of the block and insuring a firm purchase of one block upon the other when the adhesive is set.

With these and further objects in view as will hereinafter in part become apparent and in part be stated, the invention comprises certain novel constructions, combinations and arrangements of parts as subsequently specified and claimed.

In the accompanying drawings,—

Figure 1 is a side elevation of a wall lining constructed according to the present invention, and composed of a plurality of interfitting blocks constructed according to this invention.

Fig. 2 is a perspective view of a number of the wall lining blocks of this invention separated and shown in their relative posi-

tions for assemblage to form a corner of a wall lining or the like.

Fig. 3 is an enlarged side elevation, partly in section, of one of the blocks, showing the crossed arrangement of the corrugated sheets and the interposed plain sheets which form one of the sections of the block.

Fig. 4 is a fragmentary, enlarged section through the meeting ends of a pair of the blocks, showing the application of the plastic adhesive to the abutting ends.

Fig. 5 is a fragmentary section taken substantially on the plane indicated by the line $x-x$ of Fig. 4, showing a longitudinal section through the joint between a pair of abutting blocks.

Referring to the drawings by numerals, the wall lining is composed of a plurality of blocks or sections 10 adapted to be assembled as shown in Fig. 1 to provide a wall lining of the desired extent. The blocks 10, as shown to advantage in Figs. 2 and 3, each comprise a pair of sections which are offset diagonally relatively to each other and secured in face engagement to form a block having outstanding flanges 11 and 12 at adjacent sides and of a thickness equal to substantially that of one-half the thickness of the block. A pair of blocks may thus be interfitted or overlapped at their flanged edges, and as the flanges 11 and 12 are formed on adjacent edges or sides, it is apparent that one block is capable of interfitting in either straight or rectangular relation with two other blocks, as indicated in Fig. 2, for forming a corner of the wall or lining. The said other two blocks 10 each have one of their flanges interfitting with the respective flanges 11 and 12 of the first block, and when the two blocks are arranged in right-angular relation to the first block the free flanged edges of the two blocks may be interfitted to complete the corner structure.

The two sections of each block are formed with corrugated faces 13, and the faces 13 are adapted to be brought together in assembling the sections of the blocks and interfitted, as shown in Fig. 4, to maintain the sections from relative displacement and to form relatively large surface areas for the adhering faces of the sections. The projecting edge of one section which forms the flange 11 exposes the corrugations beyond the marginal

edge of the other section and the corrugations may extend, as shown in the present disclosure, substantially in parallelism with the marginal edge of the other section. The 5 adjacent flange 12 exposes the corrugations as extending outwardly from the adjacent edge of the other section, and the corrugated faces of the flanges provide relatively large surface areas for not only firmly interlocking with adjacent blocks but also to receive 10 a relatively large quantity of adhesive for insuring a tight sealed joint between adjacent blocks. It is obvious that the other section of the block provides similarly arranged 15 and formed flanges 11 and 12, the other flanges, however, facing toward the opposite side of the block.

As shown in Fig. 3, each section of the block 10 is formed of a plurality of corrugated fibrous layers 14 arranged with their corrugations extending in directions at right angles to each other to form a crossed and inter-braced structure. The corrugated sheets 14 have interposed therebetween plain, 20 flat sheets 15 of any desired thickness for maintaining the corrugated sheets in proper form, and for forming in the block section an extremely large number of independent air cells. The corrugated and flat sheets 14 and 15 are thus alternately superposed one 25 upon the other to form a section of the desired thickness, the laminations preferably terminating in a flat smooth sheet at the outer face of the block.

30 The air cells formed in the block sections are closed when the blocks are assembled, and a plastic adhesive 16 is placed between the meeting ends of the blocks in sufficient quantity to be forced into the cells or pores 35 of the sections and provide, when the adhesive sets, a relatively strong, substantially integral joint for the blocks. The adhesive also insures the sealing of the cells or spaces and thus entraps air therein so that an effective insulation is formed. The blocks may 40 be made of any desired size and shape, and any desired number of the same may be employed for building up a wall or lining of the required dimensions. The sections of 45 each block may also be of the desired thickness by superposing the desired number of layers 14 and 15 so that the completed wall or lining may be given the desired thickness.

50 What I claim is:—

55 1. As an article of manufacture, a fibrous wall lining unit comprising a pair of superposed offset sections secured together in face engagement and having interfitting corrugations at their meeting faces for interlock-

ing the sections and forming a flange at the 60 edge of the unit with a corrugated face.

2. As an article of manufacture, a fibrous wall lining unit comprising a pair of superposed diagonally offset sections secured together in face engagement and with corrugated abutting faces adapted to interfit and form outstanding flanges at adjacent edges of the unit with corrugations extending in directions at right angles to each other.

3. In a wall structure, the combination of 70 a pair of units having marginal flanges adapted to overlap and provided with air cells in the units opening at the marginal edges thereof, and a plastic adhesive embedded in the meeting edges of the units and 75 adapted to close the air cells and secure the units together.

4. In a wall structure, the combination of 80 a pair of fibrous units having air cells there-in opening through the marginal edges of 85 the units, the units provided with flanges at their marginal edges adapted to overlap, and a viscous adhesive packed between the meeting edges of the units and into the ends of the air cells for uniting the units and 90 closing the air cells to form dead air spaces in the wall structure.

5. As an article of manufacture, a fibrous wall unit comprising a pair of sections and 95 each section composed of superposed alternate flat and corrugated fibrous sheets secured together to form cells in the sections, the sections terminating at one face in a corrugated sheet and at its other face in a 100 flat sheet, and the sections secured in face 105 engagement with their exposed corrugations interfitted.

6. As an article of manufacture, a fibrous wall unit comprising a pair of superposed sections offset relatively to each other for 110 forming a marginal flange on the unit, each section composed of a plurality of layers of cellular fibrous material with the corrugations of the alternate layers extending at right angles to each other for strengthening 115 the section, and with corrugations exposed at one face of the section for interfitting engagement with the exposed corrugations of the other section and to provide a corrugated exposed surface to the marginal flange.

In testimony whereof I affix my signature in presence of two witnesses.

LINZY HICKS.
